C. S. BUSHNELL

TRAIN CONTROL

Filed June 28, 1924

UNITED STATES PATENT OFFICE.

CHARLES S. BUSHNELL, OF ROCHESTER, NEW YORK, ASSIGNEE TO GENERAL RAILWAY SIGNAL COMPANY, OF ROCHESTER, NEW YORK.

TRAIN CONTROL.

Application filed June 28, 1924. Serial No. 723,047.

This invention relates to train control systems of the three-position or polyphase continuous inductive type, and more particularly to means for economically increasing the efficiency of the inductive influence receiving apparatus used for detecting line phase current in the track rails.

Generally speaking, a continuous inductive train control system of the three-position or polyphase type consists of a three-position relay connected to suitable amplifying devices on the car, for which the current in one of the phases of this relay is inductively detected from current flowing in opposite directions in the two rails in front of a train corresponding to the usual track circuit current, and in which the current in the other phase flows in response to current detected flowing in the two track rails in multiple, both of these currents being amplified by suitable amplifying means; for various reasons, possibly because a single phase or single element relay for detecting line phase current is employed in addition to the polyphase relay, or because the track phase current is cut down to a lower value or a less number of stages of amplifying apparatus are employed, it may be considered desirable to pick up inductively as much potential due to line phase current flowing in the two track rails in multiple as possible; and in accordance with the present invention it is proposed to employ four influence receiving coils for detecting line phase current and two influence receiving coils for detecting track phase current. More specifically it is proposed to have two receiving elements at the front of the locomotive, between the locomotive and tender and at the rear of the tender respectively, of which the middle pair of coils are always connected cumulatively for currents flowing in the same direction in the two track rails, the rear pair of elements are similarly connected and in series with the middle pair and in which the front pair of elements are connected so that voltages induced therein due to track phase current flowing in one direction in one rail and the other direction in the other rail are cumulative, regardless of whether the engine and tender unit runs pilot or tender first.

Other objects, purposes and characteristic features of the invention will appear as the description progresses.

In describing the invention in detail reference will be had to the drawing which illustrates conventionally and in a diagrammatic manner the car carried and trackway apparatus of one embodiment of the present invention.

The trackway apparatus is illustrative of a typical three-position continuous inductive train control system and only a very brief description thereof is deemed necessary. The usual track rails 1 have been shown divided into blocks by insulating joints 2, the block I and the adjacent ends of two other blocks H and J being shown. Since the various blocks are the same, like parts of each block are designated by like reference characters having distinctive exponents. At the entrance end of the block I is shown a track relay 3, of the two element type having one of its coils connected across the track rails and having its other coil connected to the secondary winding of a transformer 4 receiving energy from the line wires 5 connected to a suitable source of alternating current. The exit end of the block I is provided with the usual track current source comprising a transformer 6 having its secondary winding connected across the track rails through the usual impedance 7. This relay and trackway source correspond to the elements making up the usual track circuit whereby current is adapted to flow down one rail through the relay 3 and back through the other so that this relay may be shunted by a train moving in the block.

In addition to the track phase current there is provided means for conducting current through various sections of the block I through the two rails in multiple, which current is considerably displaced in phase with respect to the track phase current, so that if both of these currents are detected and applied to the coils of a polyphase relay of the induction type on the car, such relay may be actuated. In the arrangement shown this line phase current is caused to flow in the two rails in multiple by having wires tapped to the middle points of balancing resistances 10, 11, 12 and 13.

The first section of the block I is normally energized by line phase current having a normal phase relation with respect to the trackway current through a circuit which may be traced as follows: beginning at the

transformer 4¹, wires 15¹ and 16¹, contact 17¹ of the track relay 3¹, wire 18, balancing resistance 10 through the first section of the two track rails in multiple to the balancing resistance 11, wires 19 and 20¹, front contact 21¹ wires 22¹ and 23¹, back to the transformer 4¹. It will be noted that deenergization of the track relay 3¹ completes the same circuit in a manner so that the current flow therein is reversed. The second section of the block, extending from the point B to the exit end thereof, is under clear traffic conditions energized by current having a normal phase relation with respect to the track-way current, and flowing in the following circuit:—beginning at the transformer 25, wire 26¹, front contact 27¹, wire 28, balancing resistance 13, the two rails in multiple of the second section of the block I, balancing resistance 12, wire 29, back to the secondary winding of the transformer 25. It should be noted that the line phase current of this second section of the block I is cut off when the block J in advance thereof is occupied and the track relay 3¹ assumes its deenergized position.

From the foregoing it will be noted that a train equipped with suitable car carried apparatus is adapted to detect both line phase and track phase current having a normal phase relation when moving in the block I when both the block I and the block J next in advance thereof are unoccupied, that such a train is adapted to pick up line phase and track phase current having a reverse relative phase relation when moving between the entrance of the block I and the point B when the next block in advance is occupied but can pick up track phase current only beyond the point B under this condition, and that a train so equipped entering the block I when this block is already occupied by another train ahead can detect line phase current only. In other words, a train equipped with a polyphase relay and suitable detecting and amplifying means would have its relay energized in a normal position when it enters a clear block, would have its relay assume the reverse position when moving in a caution block between the entrance thereof and the point B and have its relay assume the deenergized position when moving beyond the point B in a caution block or when moving in an occupied block.

Referring to the drawing in which one embodiment of the car-carried apparatus of the present invention has been conventionally illustrated, the usual engine has been shown by the wheels and axle 31 and the tender associated therewith has been illustrated by the wheels and axle 32. Suitably housed and preferably on the top of the tender is located a multiple blade reversing switch comprising an insulating rod 33 having blades 34, 35, 36, 37, 44, 45, 46 and 47.

One end of the rod 33 is slidably mounted in a support 38 and the other end is pivotally connected to the free end of a clutch arm 40 having its other end frictionally connected to a suitable shaft driven from the wheels of the vehicle; the shaft in practice would preferably be located on top of the tender. In the arrangement shown the frictional connection of this arm 40 to the shaft 41 comprises a brake shoe 42 having an extending rod 42¹ which is slidably mounted in a lug 43. This brake shoe 42 is lined by suitable friction material 48 and is spring pressed against this shaft 41 by a compression spring 49. The particular mechanism shown for operating the switch rod 43 in one direction or the other depending on the direction the tender is moving is merely a conventional illustration for showing how the various switch blades may be thrown in one direction or the other depending on the direction in which the train is traveling and in practice will take a more elaborate form to assure proper functioning throughout a long period of use.

At the front of the engine and at the rear of the tender are located cores 52 and 53 each having depending legs terminating in enlarged pole pieces serving as flux collectors. On the core 52 are contained two coils 54 and 55 and on the core 53 are contained similar coils 56 and 57. Between the engine and tender and suitably mounted on the engine is contained a core 58 having only two depending legs and having coils 59 and 60 wound thereon in a manner so that voltages induced therein due to currents flowing in the same direction in both rails are cumulative.

In order to illustrate how these various coils may be connected to amplifying devices which have their output circuits connected to the winding of a relay, a main relay MR having windings 62 and 63 has been illustrated. The winding 62 is connected to the output circuit of a track phase amplifying device TA and the winding 63 of this relay MR is connected to the output circuit of the line phase amplifying device LA. These amplifying devices TA and LA include suitable vacuum tube amplifiers or audions of special construction so as to withstand jars and vibrations, a suitable source of energy, tuning apparatus and the like, and since the present invention is not directed toward any particular type of amplifying apparatus these amplifying devices have been shown conventionally.

For the purpose of illustrating how the relay MR may be used to indicate traffic conditions ahead, suitable cab signals G, Y and R have been illustrated which are energized under clear, caution and danger traffic conditions, respectively, as is obvious from the circuits for energizing these cab signals

by the battery 65 illustrated, the relay MR being shown in its normal clear traffic condition. Also, to show how the relay MR may restrict the movement of the train in 5 a certain manner when this relay is energized into the reversed position a normally energized train control device K energized by the battery 66 has been shown; this device K when deenergized may control the train 10 in any desired manner, that is, may set up restrictive speed limits which are gradually changed with the progress of the vehicle, may apply the brakes if the train exceeds a certain low speed limit unless the brakes 15 have been manually applied by the engineer, or the like; and a similar device K¹ which is energized under both clear and caution traffic conditions but is deenergized under danger traffic conditions is provided for 20 properly controlling the train upon entering or when moving in a danger block. This device K¹ may be of construction similar to that of the device K except that it restricts the movement of the train more than does 25 the device K.

When the train is moving from left to right as indicated by the arrow, the coils on core 52 are connected to the track amplifying device TA in a manner so that voltages induced in the coils 54 and 55 due to currents flowing in opposite directions in the track rails are cumulative through the following circuit:—beginning at the input wire 70 of the amplifying device TA, wire 71, contact 35 blade 46, wire 72; coil 55, wire 73, blade 47, wires 74, 75 and 76, contact blade 44, wire 77, coil 54, wire 78, contact blade 45, wire 79 back to the other input wire 80 of the amplifying device TA. From tracing this 40 circuit it will be noted that the coils 54 and 55 of the receiving element including core 52 were traced in opposite directions as indicated by the solid arrows so that the voltages induced in these coils due to track phase current are cumulative. The circuit for impressing potentials on the line amplifying device LA when the vehicle is moving from left to right may be traced as follows:—beginning at the input lead 81 of the amplifying device LA, wire 82, switch blade 35, wire 83, coil 56 in the direction as indicated by the solid arrow, wire 84, blade 34, wires 85, 86 and 87, switch blade 36, wire 88, coil 57 in the direction as indicated by the solid 45 arrow, wire 89, switch blade 37, wire 90, coil 59 in the direction as indicated by the solid arrow, wire 91, coil 60 in the direction as indicated by the solid arrow to the wire 92 of the amplifying device LA. By observing 50 the direction indicated by the solid arrows shown adjacent to coils 56, 57, 59 and 60 it will be noted that the voltages induced in these four coils due to current flowing in the same direction in both rails cumulative. With the currents flowing in these 55

circuits as indicated by the solid arrows the relay MR will assume its normal energized position as shown in the drawing and if either the track phase or line phase circuit is reversed this relay MR assumes its reversed 70 position.

If now the engine and tender unit is turned end for end and moves from left to right, the coils 56 and 57 will be connected to the amplifying device TA to detect track phase current and the coils 54, 55, 59 and 60 will be connected in series to detect line phase current and will be connected to the amplifying device LA; this by reason of the reversal of the multiple blade reversing switch shown. 75 It is considered unnecessary to trace the circuits specified when these switches assume the reversed dotted position since these circuits may be readily traced, but it may be pointed out that with the engine and tender unit moving tender first the various pairs of coils are connected in series as indicated by the dotted arrows. 80

Having thus shown and described one specific embodiment of the invention it is 90 desired to be understood that the specific arrangement shown has been disclosed to illustrate the nature of the invention rather than the scope thereof; and that various changes, modifications and adaptions may be 95 made to adapt the invention to the particular type of train control system in connection with which it is to be used without departing from the nature or scope of the invention or the idea of means underlying the same. 100

What is desired to be secured by Letters Patent of the United States is:—

1. Car-carried apparatus for automatic train control systems of the continuous inductive type comprising, a pair of coils located in inductive relation to the track rails connected to cumulatively detect currents flowing in opposite directions in the track rails ahead of a car, two pairs of coils each pair of which is connected to cumulatively 105 detect currents flowing in the same direction in the two track rails under the car, amplifying devices for amplifying the potentials detected from said currents, electro-responsive means connected to said amplifying devices, and means for changing the connections of said coils so as to cause them to properly detect the currents in the track rails when the direction of the movement of the car is reversed. 110

2. Car-carried apparatus for automatic train control systems of the polyphase continuous inductive type comprising, a polyphase relay having two windings, an amplifying device connected to each of said windings, three pairs of inductive influence detecting coils, and means for connecting the leading pair of coils to cumulatively detect currents flowing in opposite directions in the two rails ahead of the train to one of said 125 130

amplifying devices and for connecting the other two pairs of coils in series to cumulatively detect currents flowing in the same direction in the two rails under the train regardless of the direction in which the train is moving.

3. Car-carried apparatus for automatic train control systems of the polyphase continuous inductive type comprising, a polyphase relay having two windings, an amplifying device connected to each of said windings, three pairs of inductive influence detecting coils, and means automatically operated, dependent upon the direction in which the train is moving, for connecting the leading pair of coils in a circuit to cumulatively collect energy in response to current flowing in opposite directions in the two rails ahead of the train and for connecting the other two pairs of coils to cumulatively collect energy from current flowing in the same direction in the two track rails in multiple, regardless of the direction in which the train is moving.

25 4. In an automatic train control system, the combination of trackway means for causing currents to flow along the trackway in two distinctive circuits, one of which includes the two rails ahead of the train in series and the other of which includes the two track rails in multiple, and of car-carried apparatus including three pairs of inductive influence receiving coils, each pair of which is disposed in inductive relation with the two track rails, and means controlled in response to the direction of movement of the train for connecting the leading pair of coils so that voltages induced therein due to currents flowing in opposite directions in the rails are cumulative and for connecting the remaining two pairs of coils in series in a manner so that voltages induced in these coils due to currents flowing in the two rails in the same direction are cumulative.

45 5. In an automatic train control system, the combination of trackway means for causing currents to flow along the trackway in two distinctive circuits one of which includes the two track rails ahead of the train in series and the other of which includes the two track rails in multiple, and of car-carried apparatus including three pairs of inductive influence receiving coils, each pair of which is disposed in inductive relation with respect to the two track rails, and means including a slip friction clutch of which one element is driven from the wheels of the vehicle and the other element is adapted to move into one or the other extreme position, contacts

operated by said last mentioned element for connecting the leading pairs of coils so that voltages induced therein due to currents flowing in opposite directions in the rails are cumulative and for connecting the remaining two pairs of coils in series in a manner so that voltages induced in these coils due to currents flowing in the two rails in the same direction are cumulative.

6. In an automatic train control system the combination of trackway means for causing alternating currents supplied from a transmission line to flow along the trackway in two distinctive circuits, one circuit of which includes the two track rails ahead of the car in series and the other of which includes the two track rails under the car in multiple, car-carried apparatus including two pairs of inductive influence receiving coils, one pair of which is located in front of the first axle of the car and connected to cumulatively detect currents flowing in opposite directions in the rails and the other pair of which is located behind the last axle of the car and connected to cumulatively detect currents flowing in the same direction in the two rails, and means operated by an axle of the car and effected to make the necessary changes in the connections of the pairs of coils to detect such currents when the car is turned end for end and is moved along the track in the same direction.

7. In an automatic train control system, the combination of trackway means for causing alternating currents supplied from a transmission line to flow along the trackway in two distinctive circuits, one circuit of which includes the two track rails ahead of the car in series and the other of which includes the two track rails under the car in multiple, car-carried apparatus including two pairs of inductive influence receiving coils, one pair of which is located in front of the first axle of the car and connected to cumulatively detect currents flowing in opposite directions in the rails and the other pair of which is located behind the last axle of the car and connected to cumulatively detect currents flowing in the same direction in the two rails, and means including a slip-friction clutch operated by an axle of the car and which renders the necessary changes in the connections effective to detect such currents when the car is turned end for end and is moved in the same direction along the track.

In testimony whereof I affix my signature.

CHARLES S. BUSHNELL.
